UNITED STATES PATENT OFFICE

HARRY HERTZBERG, OF BROOKLYN, NEW YORK

DUSTING MOP

Application filed February 6, 1929. Serial No. 337,867.

This invention relates to improvements in dusting mops and particularly to that type of such mops in which a loop shaped metallic frame carries the mop material.

5 It is the object of the present invention to provide a mop frame which forms a closed loop covered by a sheath of fabric having mop cords which form a heavy fringe thereon and means for quick attachment of said 10 sheath to its frame or removal therefrom.

It is another object of the invention to provide a mop frame which holds and clamps the mop sheath so that it cannot be accidentally removed from the frame.

15 It is a further object of this invention to provide a looped mop frame which yields resiliently on its forward stroke when striking a solid object or by friction against the surface which is being cleaned.

20 With these and other objects in view which will become clearer as the description progresses, the invention consists in a novel construction and combination of parts herein-after more fully described and finally pointed out in the appended claims.

25 In the drawings which form a material part of this disclosure:

Fig. 1 is a perspective front elevation of a 30 mop embodying the invention showing two separate sheaths partly assembled on the frame.

Fig. 2 illustrates the mop of Fig. 1 when 35 completely assembled.

Fig. 3 shows the mop frame illustrated in 40 Figs. 1 and 2 during the application of a single mop sheath to both arms of the frame.

Fig. 4 shows the mop of Fig. 3 completely 45 assembled.

Fig. 5 is a diagrammatic illustration of a 50 looped mop frame having overlapping arms in its rearward portion.

Fig. 6 is a diagrammatic illustration showing 55 the invention applied to a mop frame of triangular shape.

Fig. 7 is an enlarged detail elevation of the 60 resilient connector which joins the mop frame arms to the mop stick partly in section on line 7—7 of Fig. 1.

Fig. 8 is a side elevation of Fig. 7 partly 65 in section on line 8—8 of that figure.

Referring to the drawings, 10 is a helical coil of wire, having an open wound portion 10^a and a closely wound portion 10^b of smaller diameter. Portion 10^a forms a threaded socket for a mop stick 13 the bottom 55 of which leans against the first turn of 10^b which forms a stop therefor. The coil portion 10^b holds the ends of two metallic bars 11 lying flat against each other. The end portions are shaped as shown in Fig. 7 having 60 a taper portion 11^a, a wide portion 11^c and a narrow portion 11^b. Outside of coil 10 each bar 11 is bent to form a U shaped resilient arm bent in opposite direction to the other bar as shown in Fig. 3. The free ends 65 of bars 11 overlap each other for a distance and their flat sides lean against each other, end portion 11^d pressing inwardly against end portion 11^c which presses in outward direction. In this manner a continuous loop is 70 formed by the two arms without any open space therein.

The mop material 14 is bound in by tubular fabric sheaths 15 which are slipped upon 75 each one of the arm-ends 11^d and 11^e. A separate sheath 15 may be used for each arm as illustrated in Figs. 1 and 2 or a single sheath of double length as shown in Figs. 3 and 4. For applying the double sheaths to a mop frame, ends 11^d and 11^e are pressed apart 80 by hand and a sheath 15 threaded over the free end of each arm 11 so far, that the overlapping end portions remain uncovered as shown in Fig. 1. The ends are then released to snap against each other and the sheaths 85 are stretched over the overlapping arm portions to cover them as shown in Fig. 2.

A single sheath for covering both arms is applied to the mop frame as shown in Fig. 3 by threading one of its open ends on each arm and allowing an empty middle portion of the sheath to lie between the flat inner faces of 11^d and 11^e forming a reverse bend and clamping it tightly between said ends as shown in Fig. 4.

The fastening of the two frame arms 11 to coil 10 is a modification of my invention shown and described in my application for Letters Patent entitled "Holder for dusters and the like" Ser. No. 275,985 filed May 8th, 100

1928, carrying forward the same inventive concept. In the present case the arms 11 which support the mop material are formed at their ends as shown in Fig. 7 by tapering the ends of the bars at 11^a and cutting notches 5 in opposite sides thereof at 11^b. The tapered ends are forced into the open end of coil 10^b expanding the coil until the lower turns contract again when the narrow part 11^b passes 10 into the coil. The shoulder between 11^b and 11^c prevents removal of the bars 11 and fixes 15 their position longitudinally of the coil. The transverse radial pressure of the expanded turns opposite 11^c and 11^a holds the two plates 15 tightly against each other and secures the arms 11 rigidly to coil 10.

In Fig. 5 I have illustrated a mop frame adapted to be covered by a single sheath which is of single thickness on all parts of 20 the loop and in Fig. 5 I have shown the application of my invention to a mop having a triangular loop.

This novel dusting mop has the great advantage over similar devices that the frame 25 has no opening through which the mop sheath may slip and yet if desired the sheath may be easily removed from the frame. When a single sheath is used on the frame as shown in Fig. 7 that part of the mop material 30 which is exposed to the greatest wear in the central front part of the mop is of a triple thickness and tightly held against any movement on the frame.

The mop structure disclosed in this application in its use performs as a whole a novel function when sweeping a floor or wall, which 35 consists in the resilient or yielding action of the loop on its forward stroke. Both arms give and bend inward under resistance 40 offered either by the friction against the floor or more pronounced when the front part of the loop strikes any hard object.

Having thus described my invention what 45 I claim as new and desire to secure by Letters Patent is:

1. In a mop, a pair of arms joined at one end and extending at first away from and then towards each other forming a normally closed loop, the opposite free end portions of 50 said arms overlapping longitudinally of and pressing resiliently against each other, providing means for placing mop fabric between the adjacent sides of said arms by their temporary lateral separation and for clamping 55 said fabric therebetween.

2. A mop head comprising a handle engaging portion consisting of a helical coil, a pair of arms having a stem extending a limited distance into said coil, a wide body portion 60 on said stem adapted to expand some of the turns of said coil and a narrower neck portion allowing contraction of other turns near one end of said coil, the contracted turns surrounding said neck portion forming means 65 to lock said arms permanently to said coil,

said arms extending outwardly of said coil in opposite directions forming a loop and a mop fabric having a tubular portion slipped upon said arms to be supported thereby.

3. A mop head comprising a tubular mop fabric, a handle engaging portion consisting of a helical coil, a pair of bars joined to each other at one end by said coil and extending a limited distance into said coil and a narrow neck portion on said bar engaging a turn of 70 said coil, said neck portion providing anchoring means for said arms within said coil, and a loop formed by said bars outside of said coil, the opposite free ends of said bars overlapping each other providing a closure for 75 said loop and said tubular mop fabric covering said arms and said closure.

4. A mop head comprising a handle engaging portion consisting of a helical coil adapted to yield transversely, a pair of flat bars 80 pressed laterally against each other, extending a limited distance into said coil and each of said bars having coextensive recesses receiving some of the turns of the coil to lock the said bars against longitudinal movement 85 in said coil, said bars being shaped to form a loop outside of said coil and a tubular mop fabric covering said loop, the free ends of 90 said bars being arranged to yield resiliently towards the interior of said loop.

5. A mop consisting of a holding member 95 for attachment to a mop handle, a pair of resilient arms each consisting of a continuous bar and each extending from the axis of 100 said mop handle in opposite directions and forming together a looped frame, the free end of each arm overlapping the free end of the other arm, being urged to such position by the inherent resiliency of the arms, and a sheath carrying mop material threaded over 105 the end of each arm and enclosing the overlapping portions of both arms.

6. In a mop, a mop fabric having a tubular portion, a pair of arms consisting each of a resilient bar, said arms being joined to each other at one end and extending at first away from and then toward each other forming a loop, the opposite free end portions of 110 said arms being parallel and overlapping each other due to the resiliency of the arms and providing a closure for said loop within the tubular portion of the mop fabric.

Signed at Brooklyn in the county of Kings and State of New York this 4th day of February, A. D. 1929.

HARRY HERTZBERG.
